A. G. SHAVER

ROADSIDE APPARATUS FOR AUTOMATIC TRAIN CONTROL SYSTEMS

Filed May 8, 1923

UNITED STATES PATENT OFFICE.

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK.

ROADSIDE APPARATUS FOR AUTOMATIC TRAIN-CONTROL SYSTEMS.

Application filed May 8, 1923. Serial No. 637,515.

To all whom it may concern:

Be it known that I, ARCHIBALD G. SHAVER, a citizen of the United States, and resident of Chicago, in the county of Cook and State of Illinois, have invented certain new and useful Improvements in Roadside Apparatus for Automatic Train-Control Systems, of which the following is a specification.

10 This invention relates to an automatic train control system, and more particularly to a system in which energy is transmitted to train mechanism for controlling the same from a roadside apparatus operated by roadside energy; and has special reference to the provision of a roadside train control apparatus which is operated by means of roadside energy with absolute safety and with economy.

15 20 A prime desideratum of my present invention comprehends the provision of roadside train control apparatus embodying roadside circuits operated by roadside energy, in which the circuits are maintained normally open in the absence of need for traffic regulation, and are closed in the presence of such need, so that the safety factor of normally closed track circuits is combined with the energy economy factor of normally open circuits to produce safe and economical automatic control of trains.

Other desiderata of my present invention comprehend the provision of track or roadside apparatus of the induction type which may be employed, for example, with induction train apparatus of the type disclosed in my copending application Serial No. 527,567 of Jan. 7, 1922; the further provision of an induction roadside apparatus in which inductors are employed for transmitting energy to corresponding train apparatus, the said energy being obtained from a source of energy located on the roadside, with the construction such that the inductors are deenergized in the absence of movement of trains on the readbed and re-energized in the presence of such train movements, with the inductors controlled in response to traffic conditions; and the still further provision of a system of this nature in which the inductors are controlled to produce train operations corresponding to "clear", "caution" and "danger" track conditions.

55 To the accomplishment of the foregoing

and such other objects as may hereinafter appear, my invention consists in the elements and their relation one to the other, as hereinafter particularly described and sought to be defined in the claims, reference being had to the accompanying drawings forming a part thereof, and in which:

Fig. 1 is a view of one form of roadside apparatus embodying my invention, and

Fig. 2 is a view of a modified form of roadside apparatus embodying my invention.

Referring now more in detail to Fig. 1 of the drawings, I show my invention applied to a roadside apparatus of the induction type which may be employed with the induction train control mechanism disclosed in my abovementioned application. In this form of my invention the roadside apparatus may comprise sets of magnetic devices arranged in the insulated blocks or sections of the track such as A, B, C and D, the said blocks being obtained in the usual manner by subdividing the track rails 10, 11 into insulated sections, as shown in the drawings. In the construction illustrated the magnetic devices for each block preferably comprise a magnetic inert element M which in the operation of the train control system functions as a means for deenergizing or tripping the train circuits in the passage of a train thereover, and an inductor or inductors generally designated as M', which functions for operating the train circuits in response to traffic conditions.

In the system illustrated in Fig. 1, the inductor means M' comprises independent inductors 12 and 13 which function as energy transmitting devices for transmitting energy to corresponding or similar train inductors for energizing or resetting the train circuits after the same have been tripped by the inert element M, the operation, as hereinafter described more in detail, being such that when the inductors 12 and 13 of a block are both deenergized, no energy will be transmitted to the train circuits to re-energize the same, this being in response to "danger" traffic conditions to produce a "stop" condition on the vehicle; and when the inductor 12 of a block is energized, as in response to "clear" track conditions, energy will be transmitted to the train circuits to permit unrestricted movement of the

train; and when the inductor 13 of a block is energized, this being in response to "caution" track conditions, energy will be transmitted to the train circuits to produce a 5 restricted running condition of the train.

For controlling the energization of the inductors in response to "clear", "caution" and "danger" track conditions, I may provide each track section or block with a home 10 relay HR and a distant relay DR, the home relays of each section comprising track relays connected to the opposite rails 10-11 of the track, as by means of the conductors 14 and 15, and normally energized by means 15 of the track batteries 16 provided for each block, the distant relays of each block or section being controlled by a home relay of a succeeding block or section by means of a circuit which comprises a battery 17 provided for each block, conductor 18, distant relay DR of one block, conductor 19, contact 20 controlled by a home relay HR of the next succeeding block, and conductor 21.

The inductors of one block or section are 25 controlled by the home or distant relays of the next or succeeding block or section, and to this end the inductors 12 and 13 of block A for example are arranged in circuits to be described presently, which circuits are 30 operated by roadside energy and controlled by the activity of the home and distant relays of the next succeeding block in response to traffic conditions.

As hereinbefore stated, a desideratum of 35 the invention relates to the provision of roadside control apparatus in which a roadside circuit or circuits operated by roadside energy is maintained normally open in the absence of the need of traffic regulation so 40 as to obtain a maximum economy in the use of roadside energy, and is closed only in the presence of such need to obtain the safety advantages of the normally closed type of circuit. To accomplish these ends, the track 45 inductor or inductors is arranged in a circuit or circuits controlled by a home relay of the block or section individual to such inductor and controlled so that the circuit to the inductor is maintained normally open 50 in the absence of and is closed in the presence of a train in such section, the said circuit being additionally controlled by the home and distant relays of the next succeeding block in response to the traffic conditions. To accomplish this constructionally, 55 the inductor 12 in the embodiment shown in Fig. 1 is connected in a circuit including a roadside source of energy G which may be an alternating current generator, the common conductor 22, conductor 23, contact 24 controlled by a home relay HR, the said contact being normally open when the said relay is energized in the absence of a train in the block thereof, conductor 25, inductor 12, 60 conductor 26, front contact point 27 and con-

tact 28 (closed when the distant relay DR is energized), conductor 29, contact 30, contact point 31 (closed when the home relay HR is energized), conductor 32, a condenser 33, conductor 34, and common conductor 35 70 back to the generator G.

Inductor 13 is arranged in an independent circuit which may have parts common to the circuit described, the circuit to the inductor 13 including the generator G, conductors 75 22 and 23, contact 24 and conductor 25, inductor 13, conductor 36, back contact point 37 (open when the distant relay DR is energized and closed when the same is deenergized), contact 28, conductor 29, contact 30, contact point 31, conductor 32, condenser 33, and conductors 34 and 35.

With this circuit arrangement, it will be seen that normally in the absence of a train in any of the sections, the inductors 12 and 13 will be 85 in a non-energized state due to the opening of the contact 24 common to the circuits of the inductors.

When a train, however, enters upon a section such as A, the battery 16 of 90 such section is short-circuited and the relay HR of the said section is deenergized, with the effect of closing a contact 24 controlled thereby to condition or affect the circuits of the inductors to be influenced by the operation of the home and distant relays of the 95 next succeeding block such as B. It will be further seen that when a train enters the section A, for example, under "clear" roadside conditions, the home and distant relays 100 of the block B will be energized so that the inductor 12 is energized, this to transmit a "clear" indication to the vehicle mechanism; and that when the train enters block A under "caution" traffic conditions, this being 105 the case when another train is in the block C, the home relay of block C will be deenergized to deenergize the circuit of and therefore the distant relay DR of block B, this having the effect of causing the contact 110 28 to make on the back contact point 37, resulting in the opening of the circuit to the inductor 12 of block A and the closing of the circuit to the inductor 13 of such block, so that a "caution" indication is transmitted 115 to the train mechanism.

When the train enters the block A under "danger" track conditions, this being the case when another train is in the block B, the home relay HR of block B is short-circuited and deenergized, resulting in the opening of the contact 30 and the deenergizing of both inductors 12 and 13 of block A, this having the effect of failing to transmit energy to the train circuits and preventing a modification of the 120 conditions imposed upon the train by the track tripping means M.

Referring now to Fig. 2 of the drawings, I show a modification in which the track apparatus is adapted to transmit two instead of three indications in response, for 125 130

example, to a "clear" and "danger" track condition. The tracks are also subdivided into insulated blocks or sections such as A', B', C' and D', each section supplied with a track battery 37 and each provided with a home relay H'R' connected to the opposite rails 39 and 40 of the track as by means of the conductors 41 and 42 respectively. Each track section is also provided preferably with a plurality of magnetic elements comprising the inert element M² and one or a plurality of inductors M³, the said inductors comprising in the construction shown the inductor elements 43 and 44 for each section arranged in a circuit controlled by the home relay H'R' of the section individual to the inductors to close the circuit only when traffic conditions are to be impressed upon the train, and by the home relay H'R' of the next succeeding section in response to traffic conditions. The circuit for the inductors of any section may comprise the alternating current generator G', common conductor 45, conductor 46, normally open contact 47, conductor 48, condenser 49, conductor 50, inductor 44, inductor 43, conductor 51, contact 52 closed upon contact point 53 when the home relay of the next succeeding section is energized in the absence of a train in such section and opened when the relay is deenergized in the presence of such a train, as under "danger" conditions, conductor 54 and common conductor 55 back to the generator G.

The operation of the roadside mechanism will in the main be apparent from the above detailed description thereof. It will be apparent that the circuits to the energy transmitting means or inductors fed from the alternating current source of energy G or G' will be maintained open with resulting economy when traffic control is unnecessary, and will be closed to produce the effect of a normally closed track circuit system when a train moves over the roadbed.

It will be apparent that while I have illustrated the principles of my invention in connection with the particular induction circuits as shown, many changes and modifications may be made in the circuits and apparatus without departing from the spirit of my invention defined in the following claims.

I claim:

1. In combination with track rails subdivided into insulated blocks or sections, of a roadside apparatus for impressing roadside conditions on moving vehicles comprising a plurality of magnetic devices associated with

one of the track sections, one of said devices comprising a tripping element and the other a resetting inductor, a circuit for the inductor including a source of energy, a home relay connected to the section associated with the circuit and operative for normally opening said circuit in the absence of a train in such section and for closing such circuit in the presence of a train therein, and home and distant relays associated with the next succeeding track section for controlling said circuit in response to traffic conditions.

2. In combination with track rails subdivided into insulated blocks or sections, of a roadside apparatus for impressing roadside conditions on moving vehicles comprising a plurality of independent inductors for each of the track sections, a circuit for each of the inductors including a source of energy, a track relay for normally opening both circuits associated with inductors of a given section in the absence of a train and for closing the said circuits in the presence of a train in such section, a track relay associated with the next succeeding section for normally closing both of said circuits in the absence of a train in the succeeding section and for opening the same in the presence of a train therein, and a distant relay associated with the said preceding section for controlling both circuits in response to traffic conditions in the second preceding section.

3. In combination with track rails subdivided into insulated blocks or sections, of a roadside apparatus for impressing roadside conditions on moving vehicles comprising magnetic devices for each section, the magnetic devices including a tripping element and a plurality of independent inductor resetting elements, a circuit for each of the resetting elements, a track relay for normally opening both circuits associated with the resetting elements of a given section in the absence of a train and for closing the said circuits in the presence of a train in such section, a track relay associated with the next succeeding section for normally closing both of said circuits in the absence of a train in the succeeding section and for opening the same in the presence of a train therein, and a distant relay associated with the said succeeding section for controlling both circuits in response to traffic conditions in a second succeeding section.

Signed at Chicago in the county of Cook and State of Illinois this the 9th day of April A. D. 1923.

ARCHIBALD G. SHAVER.
